UNITED STATES PATENT OFFICE.

JOHN H. BELL, OF SOUTH ORANGE, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

1,387,229.

Specification of Letters Patent.

Patented Aug. 9, 1921.

Application filed April 9, 1918. Serial No. 227,567.

To all whom it may concern:

Be it known that I, JOHN H. BELL, a citizen of the United States, residing at South Orange, in the county of Essex, State of New Jersey, have invented certain new and useful Improvements in Telegraph Systems, of which the following is a full, clear, concise, and exact description.

This invention relates to telegraph systems and more particularly to telegraph transmitting systems.

An object of this invention is to provide an effective and reliable remedy for the so-called "wandering zero" effects commonly experienced in connection with telegraphic service over conductors having high electrostatic capacity, such as long land lines or cables and submarine cables.

Another object is to provide a remedy for leakage effects on telegraph circuits as usually caused on open wire lines due to dampness or wet weather conditions, the term "leak nullifier" being commonly employed in the art in referring to arrangements for overcoming such leakage effects.

In accordance with the present invention there is provided an arrangement whereby an impulse of clearing current having a polarity opposite to the polarity of a preceding signaling impulse will cause a proper opposing, neutralizing or current balancing effect in the line circuit.

This invention is illustrated diagrammatically in the accompanying drawing in which for the sake of clearness only so much of a telegraph system has been shown as will be necessary to a clear understanding of the invention.

In Figure 1 there is shown a terminal equipment for a telegraph line circuit which consists of a single line conductor and the usual earth return, arranged in a manner suitable for carrying out the features of this invention. In Fig. 2 there is shown an arrangement similar to that shown in Fig. 1 except that the terminal equipment provides for operation over a metallic telegraph circuit formed of two line conductors. Fig. 3 illustrates the theoretical effects of current impulses in a telegraph conductor in which no provision is made for clearing or compensating for the usual wandering zero effects, while in Fig. 4 of the drawing, there is shown a theoretical condition of the cur-

rents in a telegraph conductor on which the zero balancing and the leak nullifying features of the present invention have been applied.

A line conductor 1 (Fig. 1) extends from a distant station (not shown) through the winding of a line relay 2, the contacts 4 of a telegraph key 3 and a line battery 6, to earth. The battery 6 is also connected over contacts 5 of the key 3 through the winding of a relay 7 and a resistance 10, to earth. In transmitting signals from the present station, the key 3 may be operated in the usual manner. At each closure of the contacts 4 of this key the battery 6 will be connected in series with the relay 2, to the line conductor 1. Contacts controlled by the line relay 2 will be understood as arranged for the control of a reading sounder or other suitable telegraph receiving device. In addition to connecting the battery 6 with the line conductor, each closure of the key 3 also connects this battery through the local relay 7 as already described. Energization of this relay connects a battery 11 over the relay contacts 8 to charge a condenser 12. The batteries 6 and 11 are of opposite polarities. Therefore, when the key 3 is released to separate its contacts 4 and 5, in addition to cessation of current of the battery 6 to the line conductor 1, the relay 7 is released to separate its contacts 8 and establish its normal contacts 9. This action of the relay 7 connects the condenser 12 in derived relation to the line conductor 1, causing the condenser to discharge and send to line 1, an impulse of a polarity opposite to that of the preceding signaling impulse from the negative battery 6.

Referring to Fig. 3 of the drawing, the straight line A represents the true zero potential point of the line conductor, while the solid line B represents the theoretical effect of current impulses at the transmitting end of the line circuit and reading from left to right correspond with two dots, a dash and a spacing interval. The dotted curved line C represents theoretically, the shape of current waves at a distant or receiving station on the line circuit, the electrical characteristics of the line having transformed or distorted the current waves B into the condition in which they are shown by this line C. The current line C, as the impulses continue to be trans-

mitted, gradually rises on the upper or positive side of the zero line A, thereby distorting the zero line of the cable. The current conditions illustrated in this Fig. 3 of the 5 drawing would result from the usual transmitting systems which may correspond with the arrangement shown in 1, providing the equipment which consists of the relay 7 and condenser 12 were dispensed with.

10 Referring to Fig. 4 of the drawing the zero line A and the current line B correspond with the similarly designated lines in Fig. 3, while the solid line D corresponds with currents set up at the transmitting end 15 of the line by the discharge action of the condenser 12. The dotted line C shows the shape of the resulting wave at a distant receiving station after it has been transformed or reshaped due to the electrical 20 characteristics of the line, as well understood in the art. The current wave C in this figure of the drawing corresponds with the shape of a received current wave, the transmitted impulses forming which have 25 been acted upon by the current clearing or compensating effects as applied by the present invention. This resultant current wave, in addition to showing a better definition between impulses, also continues substantially balanced with respect to its current 30 values on the respective positive and negative sides of the true zero line A.

Referring to Fig. 2 of the drawing, this alternate arrangement is in general similar 35 to the first arrangement already described except that the line relay is provided with two coils respectively indicated as 2 and 22, while additional contacts 28 and 29 are provided for the relay 7. In tracing a circuit 40 through this terminal equipment, the first line conductor 1 incoming from a distant station is connected through the coil 2 of the line relay, thence through the telegraph key 3, the line battery 6 and the second 45 winding 22 of the line relay, to the line conductor 21 which also extends to the assumed distant station. In transmitting message impulses from this station the key 3 controls the inclusion of the battery 6 in series 50 relation with the line conductors 1 and 21 over the circuits already traced. At each 55 closure of the telegraph key, in addition to establishing the line circuit through its contacts 4, its contacts 5 also complete a circuit through which current from the battery 6 may traverse the resistance unit 10 and the winding of the condenser control relay 7. During the time the relay 7 is energized 60 current from the line battery 6 is connected over the contacts 8 and 28 of this relay in forming a circuit to charge the condenser 12. On the key 3 being released to separate 65 its contacts 4 in disconnecting the battery 6 from the metallic line circuit, separation of the key contacts 5 also disconnects

the relay 7. The resulting release of this relay and closure of its contacts 9 and 29 disconnect the condenser 12 from the battery 6 and connect it in bridge across the circuit formed by the line conductors 1 and 21. 70 The connective relation of the battery 6 with respect to the contacts of the condenser relay 7, are such that the condenser will be charged in opposite polarity relation with respect to the current impulses from the battery 6 to the line circuit. Therefore, at the instant the relay 7 is disconnected the condenser 12 will discharge over the metallically connected line conductors in a direction opposite to that of the signaling currents over these conductors. 75

As indicated in the drawing, the resistance 10 and condenser 12 may be of variable types and the potential of the battery 11 may also be varied. In this manner a circuit relation may be obtained whereby the relatively short current interval present when the condenser 12 discharges would be such that the residual current remaining in the line circuit following a signaling impulse would be suitably counteracted or neutralized by the current from the condenser. Such condition of balance would result in securing the well defined current line C as 90 shown in Fig. 4 of the drawing. 95

In describing the manner in which the present system may fulfil the requirements of a leak nullifier, let it be assumed that the line 1 (Fig. 1) is routed through several intermediate or way-stations, thence through a 100 distant terminal station at which a line battery similar to, but oppositely poled with respect to the line battery 6, is included in the circuit in the same manner as the battery 6. It will, therefore, be clear that during such 105 time as the line circuit may be idle, the batteries at the remote stations form an accumulative series to retain all of the line relays, as the line relay 2, energized. Assuming for purpose of illustration that low insulation may be present due to wet weather along the route of the line circuit, if now the key 3 is opened as in the operations of sending a message the battery 6 will stand disconnected and the home relay 2 will be released. It will be obvious that the positively poled battery at the distant end of the line may then continue to flow outwardly over the line circuit and through the various relays at the way-stations in proportion to the leakage present along the line conductor. This current will have a tendency to retain the armatures of the line relays at the way-stations and at the distant terminal station irrespective of the open 110 moments of the key 3 at the present terminal station. As a remedy for this condition as applied by the present invention, it will be 115 clear that on the key 3 being released to disconnect the relay 7, a discharge from the 120 125 130

condenser 12 outwardly over the line circuit 1 will be in opposite phase or differential with respect to the line battery at the remote terminal station, thereby causing a sufficient cessation in flow of current from the 5 distant line battery to permit the relays at the way-stations and the distant terminal station to release. In a converse manner, the employment of equipment at the distant 10 terminal station similar to that shown in the drawing will serve as a remedy for line leakage when messages are being sent from that station in a manner similar to that described for the transmission of messages 15 from the station shown in Fig. 1.

Referring to Fig. 2 of the drawing, the equipment for metallic circuit working shown therein may also act as a remedy for line leakage troubles which may occur from 20 the metallic circuit formed of the line conductors 1 and 21. In this arrangement it will be understood that the line relays at the intermediate stations may be connected in series with the line conductors in the same manner as the line relay coils 2 and 22 and that a 25 similar but oppositely poled battery may be serially connected in the line loop at a distant terminal station to normally form an accumulative series with the line battery 6. 30 Operation of the key 3 in controlling the transmission of impulses and also working the relay 7 to establish counter electromotive forces, results in the condenser 12 momentarily opposing the battery of the distant 35 terminal station, thereby causing a corresponding cessation of current from that battery over the leakage present along the line circuit. In this manner, the relays at the intermediate stations and also at the distant 40 terminal station may be released and therefore conditioned to respond to the key 3 irrespective of the leakage condition of the line circuit, this remedy being effective from the distant terminal station when messages 45 may be under transmission therefrom in a manner similar to that described in connection with the present station.

Although the arrangements shown and described appear to constitute a preferred 50 embodiment of this invention, it will be understood that various departures from this embodiment may be made without departing from the spirit of this invention.

What is claimed is:

55 1. In a telegraph system, a line circuit, equipment comprising transmitting and receiving devices and a source of current serially connected with said line circuit for the handling of message impulses, a condenser, 60 a relay for respectively including said condenser in bridge of said source of current or in bridge of said equipment, and means operated by said transmitter for controlling the operation of said relay.

2. In a telegraph system, a circuit formed 65 of two line conductors, a telegraph transmitter and a source of current serially connected with said line conductors for the transmission of message impulses, a condenser, a relay for respectively including said condenser 70 in bridge on said source of current or in bridge on said line circuit, and means operated by said transmitter for controlling the operation of said relay.

3. In a telegraph system, a line conductor, 75 a source of current, transmitting means intermediate said source of current and said line, a condenser, a relay for connecting said condenser to be charged by said source of current or to be connected with said line circuit, and means controlled by said transmitter to render said relay effective to establish 80 said condenser with said line circuit during periods said source of current may be disconnected from the line.

4. A telegraph system comprising a line, 85 a source of current, a condenser normally connected with said source of current, a transmitting key, and a relay controlled by said transmitting key and adapted upon its deenergization to connect said condenser with said line whereby a current impulse of a polarity opposite to that of the line current present at the remote station traverses said line.

5. In a telegraph system, a metallic line circuit formed by two conductors, a terminal station comprising a receiving means, a transmitting means and a source of line current included in series with said line conductors, intermediate stations comprising receiving and transmitting devices connected serially with said line conductors, a distant terminal station equipped in a manner identical with the station described, at which the line battery is connected to form an accumulative series with the line battery at the first terminal station, a condenser and a relay at each terminal station, and means controlled by the associated transmitter for rendering said relay effective to respectively connect said condenser to be charged from the associated source of current or to discharge in series with said line conductors in opposite polarity relation with respect to the line battery at the distant terminal station.

6. In a telegraph system, a line conductor, a terminal station comprising receiving and transmitting devices, and a source of current 120 connected serially with said line conductor, intermediate stations comprising receiving and transmitting devices connected serially with said line conductor, a distant terminal station comprising equipment identical with the equipment described at which the polarity of the line battery is such that an accumulative series will be formed between the

batteries of the terminal stations, a condenser and a relay at each terminal station, means controlled by said relay for connecting said condenser to receive a charge from 5 the associated battery, means operated by a terminal transmitter for controlling the associated relay, and means controlled by said

relay for connecting said condenser to discharge over said line circuit in opposing polarity relation with respect to the line 10 battery at the distant terminal station.

In witness whereof, I hereunto subscribe my name this 5th day of April A. D., 1918.

JOHN H. BELL.
